CLAIM

(58) **Field of Classification Search**

The ornamental design for a hot press module of a heating machine, as shown and described.

USPC D8/29.1; D10/83; D13/123, 133;
D15/122, 126, 128, 135, 136, 140, 144,
D15/144.1, 144.2, 146
CPC .. B23K 3/0653; B23K 3/087; B23K 2201/42;
H05K 3/3457

FIG. 1 is a front elevation view showing my new design for a hot press module of a heating machine;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a top, front, right perspective view thereof;
FIG. 8 is a top, rear, left perspective view thereof;
FIG. 9 is a bottom, front, left perspective view thereof; and,
FIG. 10 is a perspective view showing the claimed design in use.

See application file for complete search history.

The broken lines shown are for the purpose of showing environmental structure and form no part of the claimed design.
